HOUSING FOR AN INPUT/OUTPUT ACOUSTICAL
TELEPHONE COUPLER UNIT

Robert A. Rice, Minneapolis, Minn., assignor to Data
Communications Systems, Inc., Minneapolis, Minn., a
corporation of Minnesota

Filed Nov. 26, 1968, Ser. No. 14,679

Term of patent 14 years

Int. Cl. D14—02

U.S. Cl. D26—14

FIG. 2

FIG. 8

FIG. 3

Des. 218,313

PAGE 2

FIG. 6

FIG. 1 is a top and front perspective view of a housing for an input/output acoustical telephone coupler unit showing my new design;

FIG. 2 is a top plan view thereof;

FIG. 3 is a side elevation thereof, the side opposite being identical thereto;

FIG. 4 is a front elevation thereof on an enlarged scale;

FIG. 5 is a rear elevation on an enlarged scale; and

FIG. 6 is a bottom plan view thereof.

I claim:

The ornamental design for a housing for an input/output acoustical telephone coupler unit, substantially as shown.
